UNITED STATES PATENT OFFICE.

CARL W. KLAUMINZER, OF LAKEWOOD, OHIO.

TYPEWRITING MACHINE.

Application filed November 16, 1922. Serial No. 601,396.

To all whom it may concern:

Be it known that I, CARL W. KLAUMINZER, a citizen of the United States, and a resident of Lakewood, county of Cuyahoga, and State of Ohio, have invented a new and useful Improvement in Typewriting Machines, of which the following is a specification, the principle of the invention being herein explained and the best mode in which I have 5 contemplated applying that principle, so as to distinguish it from other inventions.

This invention relates to an improved typewriting mechanism. More particularly it comprises a typewriting machine having 15 but few parts and carrying the printing elements upon a flexible diaphragm. The apparatus is well adapted for use with a standard keyboard and is preferably provided with but a single operating lever. It is especially adapted for the use of children, but 20 may also have peculiar advantages for persons with artificial hands or arms, as well as for those of the blind who have difficulty handling multi-key machines.

25 Simplified typewriting machines have heretofore been proposed but in all such devices, a second or auxiliary lever mechanism has been employed and the main operating lever has been used for performing only 30 certain of the operations necessary to producing an imprint. The addition of keys or levers either to secure the printing impression or to move the carriage for letter spacing makes the apparatus more complicated 35 and renders it less suitable for use by children.

The principal object of my invention is to produce a typewriting machine having a minimum of parts, and which may be 40 economically manufactured in quantity. It is another object to produce a typewriter which will operate with perfect alinement, an evenness of imprint, and which will at the same time withstand careless handling. 45 It is a further object of the invention to provide for a single actuating means which fulfills the function of moving the carriage to printing position, bringing the printing character and the paper into contact and shifting the carriage to a new position. 50 Other objects of the invention will appear in the course of the following description.

To the accomplishment of the foregoing and related ends, said invention, then, consists 55 of the means hereinafter fully described and particularly pointed out in the claims.

The annexed drawing and the following description set forth in detail certain mechanism embodying the invention, such disclosed means constituting, however, but one 60 of various mechanical forms in which the principle of the invention may be used.

In said annexed drawing:-

Fig. 1 is a top plan view of the typewriting machine showing the enclosing casing; 65 Fig. 2 is a perspective view of the printing mechanism; Fig. 3 is a top plan view of the machine with the upper portion of the enclosing casing removed; Fig. 4 is a transverse sectional elevation taken along the central 70 axis of the machine; Fig. 5 is a view of the under side of the enclosing casing taken along the line 5—5 shown in Fig. 4, looking in the direction of the arrows; Fig. 6 is a 75 rear elevation, partially in section, taken along the line 6—6 shown in Fig. 4, looking in the direction of the arrows; Fig. 7 is a detail view of the casing latching device, taken along the line 7—7 shown in Fig. 4; Fig. 8 is an end view of the platen showing the line 80 spacing mechanism; Fig. 9 is a detail section view of the diaphragm supporting slide, taken along the line 9—9 shown in Fig. 4, looking in the direction of the arrows; and Figs. 10 and 11 are enlarged detail views 85 of the index pin in the lower case and upper case positions, respectively.

As is clearly shown in Figs. 3 and 4 of the drawing, the apparatus comprises a base plate 1 upon the rearward portion of which 90 is secured a casing 2 of substantially rectangular outline but having a forward face 3 bowed outwardly at its central portion and provided adjacent its lower edge with slot 4 for a purpose which will presently 95 appear. The forward portion 5 of the base plate is provided with a series of apertures 6 designed to serve as index means for causing the usual printing letters, characters and punctuation marks used in typewriting 100 to be brought into register with the printing aperture of the machine, as will herein-after be described. Spacing apertures 10 are also provided.

While the use of apertures as index means 105 has been illustrated, it is not intended to limit the positioning mechanism to the particular construction shown.

The casing is provided centrally of its upper face 7 with a shallow transverse groove 110 8 within which the carriage is adapted to ride. At a point centrally of the depressed

channelway of said groove a printing aperture 9 is formed through the top plate of the casing and at either side of said printing aperture a small opening 11 is formed through which ink may be supplied to an ink pad 12, of canvas webbing or other suitable material, positioned adjacent the upper inner face of the casing and surrounding said printing aperture.

10 Rearwardly of the said shallow groove an angle plate 13 is secured to the upper surface of the casing, its ends 14 extending slightly beyond said casing at either side. The upstanding edge 15 of said angle plate is adapted to form the slide-way for supporting the carriage and its central portion is provided with a series of serrations 16 spaced apart approximately the width of a printing character.

20 The carriage supporting slide comprises an inverted U-shaped member 21 adapted to be engaged over the upstanding edge of the angle plate and having at its rearward edge an outwardly turned section terminating in a toothed rack bar 22. Centrally of the rearward face of the supporting slide a longitudinal slot 17 is formed, the ends of which abut against a lug 18 bent rearwardly from the central part of the upstanding portion 20 of the angle plate and form the marginal stops. Secured in a housing 25 formed at the upper edge of the slide is a spring 26 having centrally a suitably shaped projection 27 adapted to engage the serrations in the top of the angle bar at a point centrally of the slide member.

30 The platen 31 comprises a roller of sheet metal, wood, rubber, or other suitable material supported upon a central bar 32, the ends 33 of which are journaled in notches 34 formed in the end members of an elongated rectangular frame 35 of sheet metal provided with an outwardly beaded marginal portion 36 for strengthening purposes adjacent its upper edge. The ends of the bar are provided with finger knobs 37. Small pins 38, seating in appropriate recesses beneath the end flanges, serve to lock the ends of the bar within said notches.

40 Secured to one end of the platen is a circular disk 41 having a plurality of outstanding projections 42 spaced the usual width for producing single spacing between lines of typewriting. A spring pressed detent 43 is provided with an aperture 44 for the central bar and is secured to the adjacent end of the frame by having its lower end engaged within a strap 45 bent outwardly from the body of said elongated rectangular frame. The free end 46 of the detent is adapted to engage within the depressions between the several projections upon such end plate.

50 The rectangular carriage frame is provided upon its rearward edge with a pair of rearwardly extending ears 51 which are pivotally secured to pins 52, which may be formed from integral projections, at each end of the inverted U-shaped slide-way immediately above the upstanding edge of the angle bar. The rearwardly extending ears are of a length suitable to permit the platen to be rocked forwardly upon said pivots to a position centrally of the shallow groove hereinbefore described. In order to provide for the proper insertion of the paper beneath the platen roll and to provide for the accurate shifting of the paper for correct line spacing, a metal shield or paper guide 55 is secured to the rearward edge of said carriage frame by means of a pair of spring supporting-arms 56. Said paper guide is adapted to extend beneath said platen roll and is provided with a pair of spaced rollers 57 adjacent its free edge. These rollers are mounted on a pin 58 secured to the paper guide and are adapted to hold the paper in firm contact with the platen roll. The shield also serves to locate the printing position of the letter, having an index upon its under side adjacent the printing point. A corresponding index will appear on the front of the carriage frame and an index pointer on the top of the casing. This permits accurate locating of points for insertions in typewritten matter.

60 The keyboard or index plate 61 on the forward extension of the base plate has each of its respective apertures marked for the appropriate printing characters and preferably these will be arranged according to the well known universal keyboard used on standard commercial typewriters. However, the scientific printer's case, or the straight alphabetical arrangement of letters, may be used if desired; and it is likewise possible to substitute a diaphragm carrying foreign alphabets and designate the printing apertures accordingly. The index plate has only one index position for each letter of the alphabet, the upper and lower case letters being selected by means of a mechanism presently to be described. The index apertures 62 are arranged in concentric arcs, the center of which is the pivot point of the single operating lever 63. This lever and its associated mechanism is swung from a point centrally of the rearward inner face of the casing and comprises a vertical pivot post 64 upon which is journaled a rigid frame member 65 projecting forwardly. The pivot post is preferably supported in ears 66 bent outwardly from a plate 67 adapted to be removably positioned in contact with the rearward inner face of the casing by means of marginal lugs 71, 72, engaging slots 73, 74, in the top plate of the casing and the rearward edge of the base plate, respectively. Forwardly turned lugs 75, upon the removable plate 67, serve to

hold the carriage shifting plates, hereinafter to be described, in operative position. The rigid frame member comprises a vertical web 81 of sheet metal having its inner 5 end wrapped about the pivot post and carries, rigidly secured to its upper edge, a horizontal plate 82 which extends forwardly some distance beyond said vertical web terminating in a forwardly projecting finger 10 83 adapted to engage a supporting track-way 84 formed on the inner front wall of the casing. The horizontal plate has secured thereto, at a point adjacent its mid-length, a transverse pivot pin 85 over the 15 ends of which a bifurcated sheet metal lever member 86 is adapted to be positioned. This lever may be stamped out of a single sheet of metal and is suitably shaped so that at its inner section it terminates in an upwardly extending knob 87 adapted to bear against the cross-wise extending plate of the operating mechanism presently to be described, while at its forward portion it extends beneath the horizontal plate and terminates in a U-shaped member or stirrup 88 having a central transverse rib 89, which is adapted to ride into a shallow transverse notch 91 upon the pivot section of the printing lever presently to be described, and to 20 thereby cause a delayed action and sudden change of position of said bifurcated lever and its associated parts.

The horizontal plate 82 is adapted to support upon its forward section the diaphragm holding frame 92 which is adapted 25 to be slidingly engaged thereover. Pivotally secured to the vertical web member adjacent the pivot post is the operating or printing lever proper 63 heretofore referred to. This lever comprises a forward section 93 and a rearward section 94, the rearward section being preferably formed as a sleeve to receive telescopically the rearward portion of the forward member. At its rearward edge the rearward portion of the lever is provided with a pair of ears 96 adapted 40 to engage upon either side of the vertical web member 81, already described, over a pivot pin 97 extending therethrough. The 45 forward section of the lever is of a length to project a short distance beyond the front face of the casing through the slot 4, heretofore mentioned, and may be drawn outwardly therethrough an adequate distance 50 to permit the index point carried at its outer end freely to engage the various printing apertures in the forward section of the frame. The diaphragm 101 is preferably 55 formed of flexible sheet rubber, although leather, light canvas, thin sheet metal, or any other suitable material, may be used. The diaphragm, when formed of material requiring circumferential support, may be fastened at its marginal edges to a rod 60 forming a loop 102 of approximately ellip-

tical outline. Upon the upper side of the diaphragm rubber type elements 103 of shallow depth are positioned. Where the diaphragm is formed of flexible sheet rubber, as illustrated, the printing characters 70 may be molded integrally therewith and the marginal edges of the diaphragm may be molded about the supporting rod.

The ends 104 of the diaphragm supporting rod are bent at right angles to the plane 75 of the diaphragm and rigidly secured to an upright member 105 upon the diaphragm supporting frame 92 by means of a supporting tongue 106 and a loop 107 struck out of said member and crimped upon the ends of 80 the rod. As shown in Fig. 9, the diaphragm supporting frame has a horizontal base section 108, forming a supporting slide for adjustable engagement with the forward end 85 of the horizontal plate 82, as has already been indicated. This horizontal base section is provided centrally of its under side with a downwardly projecting finger 109, which is adapted to slidably engage an aperture 111 formed in the forward section 90 of the operating lever adjacent its mid-length. Thus the finger permits the downward movement of the operating lever without any shifting of the diaphragm, but insures the diaphragm moving horizontally 95 as the operating lever is shifted back and forth. The diaphragm of course readily moves from side to side as the main supporting frame is turned in one direction or 100 the other.

Above the operating lever mechanism a hammer lever 115 is pivotally mounted in fixed position for vertical movement against the platen and away from the same. The hammer lever is preferably provided with a 105 pair of rearwardly extending arms 116 spaced apart so as to provide a pivot free from liability to lateral displacement. The pivot ends of the hammer lever are preferably supported on a pair of forwardly 110 extending ears 117 formed upon the plate which supports the pivot post for the operating lever. The ears are provided with V-shaped notches 118 within which the rearward edges of the respective hammer arms 115 are adapted to engage. The pivots thus are virtually knife-edge pivots and the V-shaped notches serve to limit the movement of the hammer in each direction. At 120 the point where the rearward arms of the hammer are joined to the main stem thereof, a point of attachment 121 is formed for a coiled spring 122, the operation of which will be hereinafter described.

Pivoted to one of the ears rearwardly of 125 the hammer mechanism is a cross-wise positioned plate 123 carrying centrally of its under side a depression 124 adapted to seat upon the knob-like projection 87 of the bifurcated lever heretofore described. Said 130

plate has at its forward end a finger 125 adapted to engage a cam slide-way upon the carriage shifting mechanism presently to be described. The cross-wise positioned 5 plate is provided at its forward edge with a point of attachment 126 for the coiled spring connected with the hammer lever heretofore mentioned and on its under side is provided with a downwardly stamped 10 hook 127, adapted to form a point of attachment for a vertically positioned coiled spring 128, the other end of which is secured to an outwardly pressed hook-shaped member 129 formed adjacent the lower edge 15 of the supporting plate. The last named coiled spring serves to hold the cross-wise plate in contact with the knob of the bifurcated lever. When thus positioned the cross-wise plate serves to hold the inner end of 20 the coiled hammer spring at a point below the axis of the hammer pivot. Upon depression of the operating lever the knob on the bifurcated lever will be raised, its action being delayed by the rib entering the 25 notch, as heretofore described, and will move the cross-wise plate to its most elevated position, during which movement the rearward end of the coiled hammer spring will be moved past dead center to a position 30 above the axis of the hammer pivot. As the rearward end of the spring passes dead center, the hammer will be snapped upwardly against the diaphragm and will cause the printing character positioned beneath the 35 printing aperture to be thrust against the paper and make the desired imprint thereon. Upon the release of the operating lever the parts will immediately return to their original positions.

40 The mechanism for shifting the carriage comprises a pair of sheet metal plates pivotally and slidably mounted upon the inner upper face of the casing, as is clearly shown in Figs. 5 and 6. The centrally positioned 45 plate 131 is provided with an upwardly projecting finger 132 adapted to be brought into contact with a tooth on the rack secured to the carriage, and to be shifted laterally thereafter. This plate is provided with a slot 50 133 by means of which it is pivoted loosely at its rearward end upon a pivot point 130 secured to the under side of the casing and is provided adjacent its central portion with a spring finger 134 adapted to ride against 55 the surface of the actuating plate presently to be described. Forwardly of said finger a downwardly projecting lug 135 is formed in a position to slidingly engage a cam notch formed in the operating plate.

60 The operating plate 136 is likewise loosely pivoted upon a stud 137 projecting downwardly from the inner face of the casing. It is of bell crank form, the pivot point 65 being at one of its ends. Adjacent its central portion said bell crank lever carries the

cam notch or track 138 for engaging the downwardly projecting lug upon the carriage shifting plate heretofore referred to. Adjacent its other end said bell crank lever is formed with a pair of downwardly projecting fingers forming a cam slide-way 139. This cam slide-way is adapted to be engaged by the finger extension upon the cross-wise lever heretofore described. Thus upon the elevation of the cross-wise lever in the manner heretofore mentioned, the bell crank plate will be rocked about its pivot and brought into position to actuate the carriage shifting plate, moving the same first forwardly to bring its rack-engaging finger into contact with the rack upon the carriage, and then swinging the same transversely so as to shift the carriage one notch.

At the forward end of the operating lever an indexing pin 141 is provided for insertion in the holes of the plate, serving to designate the printing characters. This indexing pin, as is clearly shown in Figs. 10 and 11, is journaled in the end of the lever but is eccentrically mounted and is provided on its upper end with a finger piece 142 which may be rotated to move said eccentric pin through an angle of 180 degrees and displace the same horizontally a sufficient distance to bring an adjacent row of printing characters under the printing aperture when said pin is engaged in the various index holes of the key board. Thus an entirely new set of characters is made available by the simple expedient of turning the finger knob at the forward end of the operating lever.

The operation of the device has already been partly indicated but will be summarized briefly to show the exact relation of the several parts.

The single lever carrying the index pin serves to control the selection of the character, the imprinting of the character upon the sheet of paper, and the shifting of the carriage, and the finger piece at the forward end of the lever serves to select upper or lower case characters as may be desired. At the end of each line the carriage must be moved back to its initial position in the usual manner. It should be noted, however, that the carriage is free to be moved in either direction at all times, except during a portion of the downward stroke of the operating lever. This provision of a free carriage is of particular advantage for younger children, for whom a carriage release would present an insurmountable difficulty.

When the appropriate letter aperture is selected upon the key board and the pin in the proper position for upper or lower case type is depressed through such opening, the end of the spring actuating the hammer will be moved past dead center with the delayed action heretofore explained and will thus

suddenly trip the hammer and cause it to be snapped against the under side of the flexible type diaphragm. The selected type thus will be brought successively into direct contact with the paper and by virtue of their upper surfaces having been brushed across the adjacent ink pads, a clear imprint of the character will be impressed upon the paper. In view of the characters being permanently secured in mathematically correct positions upon the type diaphragm, perfect alinement will be constantly maintained.

In the form of device illustrated and described, the shifting of the carriage is arranged to take place just prior to the impression of the type character upon the paper, although it is obvious that such shifting may occur after such impression has been made, should such action become desirable. This shifting of the carriage transversely one letter space is brought about through the finger pin on the plate carrying the end of the hammer operating spring, actuating the bell crank plate of the carriage shifting mechanism which, in turn, moves the carriage shifting plate forwardly and engages the projecting finger carried on said plate with a tooth of the rack bar of the carriage.

The spacing of the lines is accomplished by turning the finger knobs one or more spaces, as indicated by the movement of the end of the spring finger over the projections at the end of the platen roll. By moving the carriage to the extreme right, the end of the longitudinal slot at the rear of the carriage supporting slide abuts the central lug of the angle plate and thus insures a uniform left hand margin. A bell of conventional design may be used to indicate the approach of the carriage to the limit of its motion in the opposite direction. By means of the scale provided on the front of the rectangular frame and upon the forward edge of the paper guide, the printing point may be readily located for any intermediate point, as when it is desired to make insertions, or to write matter in indented tabular form.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a typewriting machine, the combination of a supporting casing, an intermittently shiftable carriage mounted upon said casing, the top plate of said casing being provided with a printing aperture, a flexible type diaphragm shiftable beneath said aper-

ture, a hammer releasably positioned beneath said diaphragm, and means for causing a trigger action of said hammer to produce a sharp impact upon said type dia-

70

2. In a typewriting machine, the combination of a supporting casing having a top plate provided with a transverse groove, an intermittently shiftable carriage mounted upon said casing and received within said groove, the top plate of said casing being provided with a central printing aperture and a plurality of inking apertures, a flexible type diaphragm shiftable beneath said printing aperture, an inking pad adjacent said type diaphragm and in the path of motion of said type characters, and means for causing the printing of a desired type character.

80

3. In a typewriting machine, the combination of a supporting casing, an angle bar secured to the top plate of said casing, and having a series of notches upon its upper edge, an intermittently shiftable carriage slidably engaging said angle bar, a spring member on said carriage engaging said notches and yieldingly holding said carriage against motion, a rack secured to said carriage, type selecting and printing mechanism mounted beneath the top plate of said casing, and means supported against the under side of said top plate for engaging said rack and shifting said carriage a single printing space.

90

4. In a typewriting machine, the combination of a supporting casing, a carriage mounted upon the top plate of said casing and freely movable transversely thereof, yieldable means for centering said carriage in the successive printing positions, a rack bar associated with said carriage, and means for engaging said rack bar and shifting said carriage a single printing space, said means being supported against the under side of said top plate.

100

5. In a typewriting machine, the combination of a supporting frame, type selecting and printing mechanism mounted beneath said frame, a carriage-supporting bar mounted above said frame, spaced notches formed on said carriage-supporting bar, a carriage resting upon said bar and freely movable transversely in each direction, a spring pressed member mounted upon said carriage and engaging said notches to center said carriage in successive printing positions, a rack bar associated with said carriage, and means supported against the under side of said top plate for engaging said rack bar and shifting said carriage a single printing space.

110

6. In a typewriting machine, the combination of a casing, a carriage supported on the top plate of said casing and movable transversely thereof, an impression producing mechanism operated along a fixed path,

120

130

- 5 a type diaphragm positioned below the top plate of said casing and above said impression producing mechanism, movable means supporting said diaphragm and adapted to 10 position any part of the same in the path of said impression producing mechanism, and means for actuating said impression producing mechanism.
- 6 7. A typewriting machine comprising a 15 supporting frame, a movable carriage, a plurality of guide elements associated with said frame, a single lever co-operating with said guide elements for causing the printing of the proper character and the shifting of the carriage, and a finger-piece having an eccentric pin revolubly mounted upon said lever for adapting the same to select upper or lower case characters.
8. A typewriting machine comprising a 20 supporting frame, a movable carriage, a plurality of guide elements arranged in series in concentric rows, said individual guide elements being designated to correspond with the positioning of the upper and 25 lower case characters on the universal typewriting key board, a single lever co-operating with said guide apertures for causing the printing of the proper character and the shifting of the carriage, and a finger- 30 piece having an eccentric pin revolubly mounted upon said lever for adapting the same to select upper or lower case characters.
9. A typewriting machine comprising a 35 base plate and supporting casing, a movable carriage mounted above said casing, a plurality of guide apertures formed in the forward part of said base plate, and a single lever co-operating with said guide apertures 40 for selecting the proper printing character, for causing the printing of said character and for shifting of the carriage between the printing of successive characters.
10. In a typewriting machine the combination of a casing having a top plate, an intermittently shiftable carriage mounted above said casing, the top plate of said casing being provided with a printing aperture, a flexible type diaphragm shiftable beneath said aperture, a hammer releasably positioned beneath said diaphragm and means for causing said hammer to strike a sharp blow against said type diaphragm.
11. In a typewriting machine the combination of a supporting casing, an intermittently shiftable carriage mounted upon said casing, the top plate of said casing being provided with a printing aperture, a flexible type diaphragm shiftable beneath said 45 aperture, a hammer releasably positioned beneath said diaphragm, a spring connected at one end to said hammer, and a lever carrying the other end of said spring and adapted to move the same above and below the 50 pivot point of said hammer to cause sudden movement of said hammer toward and away from said carriage.
12. In a typewriting machine the combination of a supporting casing, an intermittently shiftable carriage mounted upon said casing, the top plate of said casing being provided with a printing aperture, a flexible type diaphragm shiftable beneath said aperture, a hammer releasably positioned beneath said diaphragm, a spring connected at one end to said hammer, a lever carrying the other end of said spring and adapted to move the same above and below the pivot joint of said hammer to cause movement of said hammer toward and away from said carriage, and means for retarding the movement of said lever causing a trigger action when said lever shifts its position and a sharp uniform blow from said hammer upon the type diaphragm.
13. In a typewriting machine, the combination of a casing, a removable base plate having a portion extending forwardly of said casing, a plate for supporting the operating mechanism of said typewriting machine with the forward portion of said mechanism extending over said extension of the base plate, and lugs on the upper and lower marginal edges of said plate engaging suitable apertures in said casing and said base plate whereby said supporting plate is held in contact with the rearward inner face of said casing.
14. In a typewriting machine, the combination of a casing, a removable base plate having a portion extending forwardly of said casing, a carriage mounted above said casing, a carriage shifting mechanism, a plate for positioning said shifting mechanism and supporting the printing mechanism of said typewriting machine, and means to lock said supporting plate against the rearward inner face of said casing when said base plate is attached to said casing.
15. In a typewriting machine, the combination of a casing having a top plate, an intermittently shiftable carriage mounted above said casing, a rack bar associated with said carriage, a carriage shifting plate mounted beneath said top plate, and means associated with said carriage shifting plate adapted to be brought into contact with said rack bar at times when it is desired to shift said carriage.
16. In a typewriting machine, the combination of a casing having a top plate, an intermittently shiftable carriage mounted above said casing, a rack bar associated with said carriage, a carriage shifting plate mounted beneath said top plate and having a finger projecting through an aperture in said top plate for engaging said rack bar, and a bell crank plate mounted beneath said top plate for shifting said finger into engagement with said rack bar and causing

said carriage shifting plate to move the carriage.

17. In a typewriting machine, the combination of a casing having a top plate, an intermittently shiftable carriage mounted above said casing, a rack bar associated with said carriage, an operating lever for said machine, carriage shifting mechanism supported beneath said top plate, and means actuated by said operating lever for causing said carriage shifting means to contact with said rack bar and move said carriage one printing space.

18. In a typewriting machine, the combination of a casing having a top plate, an intermittently shiftable carriage mounted above said casing, a rack bar associated with said carriage, an operating lever for the machine, a pair of movable plates supported upon the under side of said top plate, a finger formed upon one of said plates projecting through an aperture in said top plate and engaging said rack bar, and means connected with said operating lever for moving said plates to shift said carriage one printing space.

19. In a typewriting machine, the combination of a shiftable carriage, a pivoted hammer lever, a lever positioned cross-wise of said hammer lever, connection between said cross-wise lever and said hammer lever for actuating said hammer lever, means for moving said cross-wise lever, and means actuated by said cross-wise lever for shifting said carriage.

20. In a typewriting machine the combination of a platen roll supported upon an axial rod, a series of projections associated with one end of said platen roll, a platen roll supporting frame of sheet metal bent into rectangular outline and providing journals for said axial rod, a horizontal slot formed in one end of said frame, and a strip of spring metal centrally apertured to receive said axial rod and having one end seated in said slot and the other end resiliently bearing against said projections upon the end of the platen roll.

21. An impression mechanism for a typewriting machine comprising a pivoted lever, a hammer terminal at the end of said lever,

an operating spring attached at one end to said lever, a second lever pivoted for vertical motion, the other end of said spring being attached to said second lever, and means for causing one of the points of attachment of the spring to pass the extension of a line drawn between the pivot of the lever and the other end of the spring.

22. An impression mechanism for a typewriter comprising a Y-shaped hammer bar, the two companion ends of which are adapted to form pivot points, a hammer terminal on the other end of said bar, a coiled spring connected centrally with said Y-shaped bar, and means for holding the other end of said spring and moving the same above and below the axial line of said hammer mechanism whereby said hammer is actuated to produce a sharp impact.

23. An impression mechanism for a typewriter comprising a Y-shaped hammer bar, the two companion ends of which are adapted to form pivot points, a hammer terminal on the other end of said bar, a coiled spring connected centrally with said Y-shaped bar, a member pivoted cross-wise of the path of motion of said Y-shaped bar and supporting the other end of said spring, and means for moving said crosswise member to shift the point of attachment of said spring across the axial line of said Y-shaped bar and produce a sharp impact of said hammer terminal in the direction of motion of said movable spring end.

24. A type plate for a typewriting machine comprising a supporting rod of substantially elliptical outline, a rubber diaphragm having its marginal edges molded about said rod and printing characters formed upon the upper side thereof.

25. A type plate for a typewriting machine comprising a flexible diaphragm having printing characters thereon, and a rod serving as a marginal support for said diaphragm, the ends of said rod being bent downwardly and forming a standard for attachment to the operating lever of the typewriter.

Signed by me this 7th day of November, 1922.

CARL W. KLAUMINZER.
